UNITED STATES PATENT OFFICE.

ERMINIE P. BLACK AND EARL BLACK, OF CAREY, OHIO.

MOP HOLDER.

Application filed November 13, 1926. Serial No. 148,252.

The present invention relates to mops, and more specifically to improved means for securing a mop head to a handle.

The primary object of the invention is to provide an improved mop holder operable upon the applying of a pressure to the mop handle for rigidly gripping a mop head.

A further object of the invention is to provide an improved mop holder adapted for receiving various types of mop heads, and which holder may be operated for effectively holding the mop head without necessarily first positioning a portion of the mop head between the jaws of the holder.

A further object of the invention resides in the provision of an improved mop holder embodying a pair of jaws capable of being contracted about a mop head and secured in a locked position upon the mop head by the mere placing of the jaws on the mop head and then applying pressure to the handle upon which the holder is mounted.

A still further object of the invention is to provide an improved mop holder which is of extremely simple and durable construction, and one wherein the companion jaws are of identical construction thus permitting of the jaws being constructed from the same forming die.

Other objects and advantages of the invention will be apparent during the course of the following detailed description, taken in connection with the accompanying drawings forming a part of this specification and in which drawings:

Figure 1 is an edge elevation of the improved mop holder shown applied to a suitable handle and with the jaws of the holder in a partially expanded condition.

Figure 2 is a view similar to Figure 1 but showing the jaws in a contracted position for gripping a mop head.

Figure 3 is a side elevation showing the mop holder in a position for retaining a mop head, and showing sections broken away for illustrating certain details of construction.

Figure 4 is a transverse section on line 4-4 of Figure 3.

Figure 5 is a transverse section on line 5-5 of Figure 1.

Figure 6 is an enlarged fragmentary section on line 6-6 of Figure 3 and looking in the direction of the arrows.

Figure 7 is a perspective view of one of the sections of the sliding frame for the jaws of the holder.

Figure 8 is a perspective view of one of the companion jaws of the holder.

Referring to the drawings in detail, and wherein similar reference characters designate corresponding parts throughout the several views, the letter A may designate a suitable handle to one end of which is secured the improved jaw actuator B, the handle A having slidably mounted thereon a frame C for carrying a pair of similarly formed jaws D.

The handle A, and which may be of any suitable length in accordance with the specific use to which the mop is to be applied, may be formed of any suitable material and in the example shown is of wood and of cylindrical formation.

The jaw actuator B, and which is preferably formed of maleable cast iron, embodies a substantially flat cross bar or plate 10 having formed at its central portion a cup shaped ferrule 11 of tubular formation and of a diameter to snugly receive the lower end of the handle A. A pin or other suitable fastening element 12 may be passed through the ferrule and the lower end of the handle A for rigid mounting of the actuator upon the lower end of the handle with the cross bar 10 extending transversely of the lower end of the handle and projecting laterally to each side thereof. Provided adjacent each end of the cross plate 10, and arranged in alignment transversely of the plate, are suitable guide apertures 13 preferably of circular formation and arranged with their axes extending parallel with the axis of the handle A.

The sliding frame C, and which is adapted to be slidably mounted on the handle A above the actuator B, embodies a pair of similarly formed frame sections 15 which are preferably stamped from a suitable gauge of sheet metal. Each of the frame sections 15 is formed with a semi-circular medial portion 16 and terminal plate sections 17. These similarly formed frame sections 15 when disposed with their plate sections 17 in surface contact, provide suitable jaw attaching plates 18 provided with a medially disposed sleeve 19 of a diameter to slidably fit about the cylindrical handle A.

The frame sections 15 may be rigidly secured together as by means of suitable rivets 20 which pass through the flat plate sections 17 at a point spaced but a short distance from the sleeve 19. Provided adjacent the lower edge of each of the attaching plates 18, and at points adjacent the outer ends of the plates, are elongated openings 21 having their major axes extending longitudinally of the sliding frame, and which openings are so formed as to provide independent arcuate shaped seats 22 which when the frame C is mounted upon the handle A, align with the guide apertures 13 of the jaw actuator B.

The jaws D, and which are preferably formed from spring steel wire, are of substantially U-shape in formation and each jaw is an exact duplicate of its companion jaw. Each of the jaws D embodies leg sections 25 being offset in a like direction in the major plane of the jaw as at 26, and each of the leg sections 25 is provided at its upper end with a looped eye 27 adapted to pivotally extend through one of the openings 21 of the sliding frame C and rest in one of the arcuate shaped seats 22 of the openings. By observing Figure 3, it will be seen that the eye of one of the leg sections rests in the outermost arcuate seat 22 while the eye of the companion leg section rests in the arcuate seat arranged at the inner end of the opening at the opposite end of the sliding frame. This construction has been provided for permitting of free swinging of the independent jaws without interfering contact at the upper end of the leg sections during contracting and expanding of the lower end of the jaws. It will also be observed that the offset portions 26 dispose the lower portions of the leg sections 25 in direct alignment transversely of the jaw construction and thus disposes the lower ends of the leg sections in alignment with the guide apertures 13 of the actuator B.

Formed at the lower end of each of the leg sections 25, is an arcuate shape keeper or retaining bend 28 being offset outwardly in a plane at a right angle to the major plane of the jaw, and in a parallel plane with the plane of the eyes 27. These outwardly offset bends 28, when the jaws are in assembled relation, extend in a direct opposite direction to one another as will be observed in Figures 1 and 2. Directly below the arcuate shaped bends 28, the wire is bent laterally for forming angularly extending feet 29 joined at their lower ends by a cross section 30. These angularly offset feet 29, and which are bulged outwardly intermediate their ends as at 31, form stops 32 for limiting upward sliding movement of the jaws through the guide apertures 13 in the actuator B. The bulges 31 of the feet 29 are for disposing the cross sections 30 in a posi-

tion whereby the same will contact, or nearly so, when the jaws are in their contracted positions.

In attaching of the mop head E to the holder, the sliding frame C is first slid toward the actuator B, and which sliding movement of the anchor will cause the leg sections 25 to slide through the guide apertures 13 in a manner for moving the lower end of the jaws D away from one another. The frame C is slid toward the actuator B until the offset 26 of the jaws engage the upper surface of the cross plate 10, and act as stops for limiting expansion of the lower end of the jaw construction. The spaced cross sections 30 of the jaws may then be placed on the mop head E at any desired point and by pressing downwardly on the handle A, the actuator B will be guided downwardly along the leg sections 25 to a position beneath the oppositely arcuated bends 28 and be limited in its downward movement by the stops 32 formed directly beneath the bends. By observing Figure 2, it will be seen that the oppositely arcuated bends 28 will serve for preventing movement of the actuator B upwardly along the leg sections 25 and thus lock the jaws in clamping engagement with the mop head E. When desiring to remove the mop head from the holder, the operator merely moves the sliding frame C toward the actuator B and which movement of the frame will spread the lower portions of the jaws for releasing the grip upon the mop head.

It will be seen that the expansion and contraction of the lower portion of the jaw construction is accomplished by movement of the pivotal connection of the jaws toward and away from the fixed actuator B through which the arms of the jaws slidably extend.

A second method of clamping the jaws about the mop head E, would be to place a portion of the mop head between the spread lower ends of the jaws and then by grasping the sliding frame C pull the frame upwardly along the handle A until the cross plate 10 engages beneath the oppositely arcuated bends 28.

From the foregoing description it will be apparent that an extremely simple and efficient mop holder has been provided embodying features whereby a mop head may be easily clamped between the jaws of the holder without necessarily handling of the mop head for positioning within the holder, and one wherein the jaws are yieldably held in clamping engagement with the mop head against accidental release of the mop head from the jaws of the device.

Changes in detail may be made to the specific form of the invention herein shown and described, without departing from the spirit of the invention or the scope of the following claims.

We claim:

1. In a device of the class described, the combination of a handle, a cross plate fixedly carried by one end of the handle and having 5 transversely spaced guide apertures provided adjacent each end thereof, a sliding frame mounted on the handle and provided with elongated openings each being provided with a pair of arcuate shaped seats and a 10 pair of cooperating swab retaining jaws, each including leg sections pivotally connected to said frame at one of its openings and slideable in said guide apertures, said leg sections being provided at their lower ends 15 with arcuate shaped keeper bends and above said bends with offsets for permitting of the pivotal movement of the upper ends of the sections on the arcuate seats of said anchor.
2. In a device of the class described, the 20 combination of a handle, a cross plate fixedly

carried by one end of the handle and having transversely spaced guide apertures, a frame having a sleeve for slideable mounting on said handle and provided with attaching plates, said attaching plates at their outer ends being provided with elongated openings having their major axes extending at a right angle with the axis of said sleeve, and a pair of cooperating swab retaining jaws, 25 each including leg sections pivotally connected at their upper ends to said attaching plates at their elongated openings and slideable in said guide apertures of the cross plate, said leg sections being provided at 30 their lower ends with arcuate shaped keeper bends adapted for locking engagement with said cross plate for retaining said jaws in clamping position about a mop head. 35

ERMINA P. BLACK,
EARL BLACK.
